US0D1080092S

(12) **United States Design Patent** (10) **Patent No.:** **US D1,080,092 S**
(45) **Date of Patent:** **** Jun. 17, 2025**

(54) **PET TOY**

(71) Applicant: **Ying Wang**, Shanghai (CN)

(72) Inventor: **Ying Wang**, Shanghai (CN)

(**) Term: **15 Years**

(21) Appl. No.: **29/986,551**

(22) Filed: **Jan. 17, 2025**

(30) **Foreign Application Priority Data**

Jan. 2, 2025 (CN) 202530000603.0

(51) **LOC (15) Cl.** **30-11**

(52) **U.S. Cl.** USPC **D30/160**

(58) **Field of Classification Search**

USPC D30/158, 160, 199; D21/398, 455, 456,

D21/468

CPC A01K 15/025; A01K 15/026

See application file for complete search history.
